UNITED STATES PATENT OFFICE

FRANK W. MEYER, OF OSHKOSH, WISCONSIN, ASSIGNOR TO THE OSHKOSH TRUNK COMPANY, OF OSHKOSH, WISCONSIN, A CORPORATION OF WISCONSIN

WARDROBE TRUNK

Application filed April 2, 1926. Serial No. 99,187.

This invention relates to wardrobe trunks, and consists in the matters hereinafter described and claimed.

In the accompanying drawings—

5 Fig. 1 is a front view of my improved trunk with the doors of the wardrobe and drawer or chiffonnier sections open;

Fig. 2 is a top plan view of the trunk as shown in Fig. 1;

10 Fig. 3 is an enlarged vertical sectional view taken on line 3—3 of Fig. 2 through the chiffonnier section, the door therefor being shown as closed;

Fig. 4 is a horizontal sectional view taken 15 on line 4—4 of Fig. 1;

Fig. 5 is a front view of the latch assembly for the door of the chiffonnier section;

Fig. 6 is a horizontal sectional view taken 20 on line 6—6 of Fig. 5;

Fig. 7 is a front view, with parts in section, 25 of one of the locks for the door of the wardrobe section;

Fig. 8 is a vertical sectional view taken on line 8—8 of Fig. 4 to show the endwise movable actuating bars and associated bolts of the main locking mechanism;

30 Figs. 9 and 10 are enlarged detail sectional views taken on lines 9—9 and 10—10, respectively, of Fig. 8; and

Figs. 11 and 12 are sectional and elevational 35 views, respectively, of a modified form of structure for actuating the bolts of the locking mechanism, Fig. 11 being taken on line 11—11 of Fig. 12.

40 My improved trunk has a rigid body, designed to stand on one end in the manner of wardrobe trunks. The body is divided vertically into two compartments 1, 2 by an upright partition wall 3 arranged at right-angles to the rear wall 4 and parallel to the side wall 5 of the trunk, as shown in Fig. 4. The compartment 1 opens through the front of the trunk so that drawers 6, 6 may be slid end-

45 wise into and out of the same. The drawers are arranged in a tier in the compartment 1 and make the same the chiffonnier section of the trunk. Suitable guides or supports are provided in the compartment 1 for the drawers to slide on, as usual in trunk design.

50 For the section 1, I provide a door 7,

hinged along one vertical edge, as at 8, 8, to the side wall 5 adjacent the open end of the section, as shown in Figs. 1, 2, and 4. The lowermost drawer 6 extends down to the bottom wall 9 of the trunk, while the uppermost drawer extends to the top wall 10 of the trunk, thus making the tier of drawers occupy the full height of the section. By reason of this fact, it is necessary to have the door 7 of a length to extend from the top to the bottom of the trunk; that is, from the top wall 10 to the bottom wall 9, as shown in Figs. 1 and 3.

55 The section 1 has an outwardly projecting strip 11 at its open end. The member 11 extends along the side, top, and bottom walls of the trunk section, as shown. The door 7 is shaped to have its portions 12, 12 overlap the member 11 on the outside when the door is closed. These members 12 abut against the front edges of the top, bottom, and side walls 60 of the sections, and the door carries metal strips 13 to overlap the joints when the door is closed, as shown in Fig. 3. The bottom wall 9 of the trunk is spaced above the floor by casters 14, so that the lower end of the door may swing beneath the lower portion of the member 11, as shown in Fig. 3. The casters 65 may be in the form of balls so that the trunk may be readily moved about the floor in any direction.

70 The compartment 2 opens through the side of the trunk opposite the side wall 5, and is equipped with extensible trolleys 15, 15 and a follower 16 to make the compartment serve as the wardrobe section of the trunk. The rear wall 4 of the trunk extends on opposite sides of the partition 3 to the full extent of the compartments 1 and 2, as shown in Fig. 4. By reason of the fact that the compartment 1 opens through the front of the trunk, the front wall 4^a extends only from the partition 3 to the opening of the wardrobe section 2, and thus is shorter than the wall 4.

75 For the wardrobe section 2, I provide a door 17 hinged at 18 to the rear wall 4. Set in the open end of the section 2 and secured to the front, rear, and bottom walls of the trunk, is a substantially U-shaped frame 19. This frame extends outward from the section, and it is overlapped by the marginal por-

100

tions 20 of the door 17 when the latter is closed. The portions 20 close against the opposed edges of the trunk walls defining the section or compartment 3. These walls include the 5 front, rear, and bottom walls of the trunk and a lid or closure 21 for the upper end of the section. This closure is hinged at 22 to the adjacent edge of the permanent top wall 10 of the section 1, as shown in Figs. 1, 2, and 8. 10 The wall 10 extends beyond the partition wall 3 so that the closure 21 is not hinged to said top wall along the line of the partition. The door 17 carries a surrounding metal strip 23 to overlap all the walls defining the section 2 15 when the lid 21 and the door 17 are closed.

To simultaneously lock and unlock both of the doors 7 and 17, I provide a locking mechanism common to both doors. This mechanism has all of its moving parts 20 mounted on and supported by the short front wall 4^a, and therefore is intermediate the doors and is in position to readily reach the free vertical swinging edges of the doors which close against the front wall 4^a. With 25 the door 7 hinged to the side wall 5, said door is swung away from the front wall 4^a in opening the door and does not swing back against said wall to interfere with operating the locking mechanism.

30 The locking mechanism includes an end-wise movable means inside of the front wall 4^a and extending vertically along the same. This means is composed of upper and lower bars 24, 24, with the upper bar having its 35 upper end pivoted to a crank arm 25 fixed to an axis member 26 extending through and rotatably mounted in the front wall 4^a, as shown in Fig. 10. A plate 27 is fixed on the axis member 26 on the outside of the wall 4^a 40 and has a hasp 28 hinged to it, as shown. The hasp carries a key operable lock 29 to enter a socket 30 on the outer side of the vertical swinging edge of the door 17 when the latter is closed and locked. To reach this 45 socket, the hasp 28 is turned into a horizontal position extending across the meeting edges of the wall 4^a and door, as indicated by the dotted lines in Fig. 1.

On the outside of the wall 4^a along its up- 50 right edge against which the door 17 closes, are a set of spaced locking fixtures 31, 31. Each fixture houses a locking member 32 carried by an axis member 33 extending through and rotatably mounted in the wall 55 4^a, as shown in Fig. 7. The members 33 are connected with the bars 24 by links 34. The upper bar extends to the intermediate link 34, while the lower bar extends from said link to the lower one and is pivoted thereto, 60 as shown in Fig. 8. The adjacent ends of the bars 24 overlap at the intermediate link and are pivoted thereto by a common pin. This connection is made so that the links will be turned on moving the bars. The door 65 17 is provided along its vertical swinging

edge with a set of inwardly projecting lugs 35, 35, one for each of the members 32 and having eyes therein to receive the hooks on said members, as shown in Fig. 7. Turning the hasp 28 from the vertical position shown in full lines in Fig. 1 to the horizontal position shown in dotted lines, moves the bars 24 and turns the members 32 to carry their hooks into the eyes of the lugs 35 to lock the door 17. Reversing the action unlocks the door, as is apparent. The locking mechanism so far described is covered by my prior patents Reissue No. 14,143, granted May 30, 1916, and No. 1,454,329, granted May 8, 1923, the latter relating specifically to the outside lock assembly as detailed in Fig. 7. 70 75 80

Arranged inside of the front wall 4^a are bolts 36, 36. These bolts are at the opposite ends of the set of bars 24 and have pivotal connection with the crank 25 and lower bar, respectively, so as to be given endwise movement in the actuation of said bars. The bolts extend toward the upright edge of the wall 4^a, against which the door 7 closes, and there operate through a cleat 37 along the inside 85 of the front wall adjacent the edge referred to, as clearly shown in Fig. 9. These ends of the bolts 36, 36 are supported in loop shaped brackets 38, 38 applied to the inside 90 of the wall 4^a at the cleat, as shown in Figs. 8 and 9. 95

For these bolts 36, the door 7 carries apertured lugs 39, 39, which extend across the associated edge of the door from the metal strip 40 at such edge. The front wall 4^a is provided with slots 41 so that the lugs 39 may extend through the wall and be in position to receive the outer or free ends of the bolts 36 when the door is closed, as shown in Fig. 9. In the structure illustrated, two bolts 36 are employed. These serve to lock the door 7 closed adjacent their upper and lower ends. For the middle portion of the door, I provide a spring pressed latch member 42 to co-operate with a socketed keeper 43 on the outside of the front wall 4^a. This latch locks the middle portion of the door closed and prevents the door from gapping at its center. This latch is also used to hold the door closed when the bolts 36 are withdrawn 100 105 110 from the lugs 39. 115

By the structure described, the doors 7 and 17 of the chiffonnier and wardrobe compartments, respectively, may be locked and unlocked simultaneously by merely being required to turn the hasp 28. This avoids the necessity of having a separate set of independently operable locks for each door, as heretofore required in trunks of this general type. Thus locking and unlocking the two doors is greatly facilitated by having only one member to grasp and actuate, and that member being located adjacent the top of the trunk is conveniently located for grasp- 120 125 130

ing without bending or stooping down to reach it.

With the wardrobe and chiffonnier sections located in the trunk body, said sections may be combined in a rigid structure, thus increasing the strength of the trunk and making it much more secure than possible in wardrobe trunks of the type having the wardrobe and chiffonnier sections hinged together and swingable toward and from each other in closing and opening the trunk. Moreover, in having the wardrobe and chiffonnier sections combined in the trunk body, access may be readily had to said sections without being required to swing the sections apart, as heretofore. With the sections combined in a rigid body, floors are not scratched or marred nor rugs gathered between the sections when opening and closing them, as they need not swing toward and from each other as in center opening trunks.

With the lock arrangement shown in Fig. 8, the bolts are given an angular movement on being moved into and out of locking engagement with the lugs 39 on the door 7. To gain a straight line movement for this purpose and thus insure registration at all times between the lugs and bolts, I provide the structure shown in Figs. 11 and 12.

Outside of the wall 4^b is a hasp 28 as before. This hasp rotates an axis member 42, which has a gear 43 on the inside of said wall. The teeth of the gear engage rack teeth 44 on the associated bolt 45. The gear shown has two teeth with flat surfaces 46, 46 on opposite sides thereof to stop against the bolt and limit the turning of the gear. To hold the bolt engaged with the gear, I provide a plate 47 loose on the axis member and extending across the inside of the bolt. This holds the bolt from rubbing against the wall 4^b. The plate has an outwardly and upwardly extending flange 48 to engage about the under side of the bolt to hold it against the gear. At the upper bolt, the gear is above the bolt; while at the lower bolt the gear 43^a is below the bolt 45^a. In the latter case, the gear 43^a is on the axis member 33 of the lowermost locking fixture 31, as shown in Fig. 12, and the plate 47^a has its flanged portion 48^a engaging over the upper edge of the bolt, as shown at the lower end of Fig. 12.

With the doors 7 and 17 extending the full height of the trunk, the doors may be braced and be maintained rigid by the inwardly extending marginal portions 12 and 20, respectively, because the lower parts of these portions may swing under the bottom wall of the trunk in closing the doors. Moreover, these lower parts in swinging under the bottom serve to hold the doors from springing or warping outward to make unsightly bulges and gaps, as would be allowed should the doors terminate short of the bottom wall.

The details of structure shown and de-

scribed may be variously modified without departing from the spirit and scope of my invention.

I claim as my invention:

1. A wardrobe trunk having a rigid body adapted to stand on one end and divided vertically into outwardly opening wardrobe and chiffonnier sections, two doors, one for each section and hinged to the body, and a locking mechanism for simultaneously locking and unlocking both of said doors, said mechanism having a single actuating member in the form of a locking hasp for one of the doors and movably mounted on the outside of the trunk body. 70

2. A wardrobe trunk having a rigid body adapted to stand on one end and divided vertically into outwardly opening wardrobe and chiffonnier sections, two doors, one for each section and hinged to the body, said body having an upright outside wall between and against which the doors close, and a locking mechanism carried by said wall and co-operating with the free vertical swinging edges of said doors for simultaneously locking and unlocking both of said doors, said locking mechanism having a single actuating member in the form of a locking hasp for one of the doors and rotatably mounted on the outside of said wall. 80

3. A wardrobe trunk having a rigid body adapted to stand on one end and divided vertically into wardrobe and chiffonnier sections opening outwardly through the front and one side, respectively, of the body, said body having upright, front, rear, and side walls defining said sections, with the front wall shorter than the rear wall and confined to one of the sections, two doors, one for each section and hinged to the side and rear walls, respectively, so as not to open against said front wall, and a locking mechanism mounted on said front wall for simultaneously locking and unlocking both of said doors along the adjacent edges thereof. 100

4. The combination with a wardrobe trunk having a rigid body adapted to stand on one end and divided vertically into outwardly opening wardrobe and chiffonnier sections with two doors hinged to the trunk body, one for each section and closable toward an upright wall of the body between said doors, of a locking mechanism for said doors, said locking mechanism being carried by said wall and co-operating with both doors for simultaneously locking and unlocking the same, said locking mechanism having an endwise movable means inside of said wall and a single locking hasp outside of said wall, said hasp being associated with one of the doors and connected with said means for actuating the same. 115

5. The combination with a wardrobe trunk having a rigid body adapted to stand on one end and divided vertically into outwardly 120

opening wardrobe and chiffonnier sections with two doors hinged to the body, one for each section and closable toward an upright wall of the body between said doors, of a locking mechanism for said doors, comprising locking members on the respective doors at the free vertical swinging edges thereof, two sets of movable locking members, one for each door and mounted on said wall between the doors, a locking hasp at the outside of said wall for one door, and means connecting the hasp with both sets of movable locking members whereby the same may be moved simultaneously into and out of locking engagement with the locking members on both doors.

6. The combination with a wardrobe trunk having a rigid body adapted to stand on one end and divided vertically into outwardly opening wardrobe and chiffonnier sections with two doors hinged to the body, one for each section and closable toward an upright wall of the body between said doors, of a locking mechanism for said doors, comprising bolts and hooks mounted on said wall for the respective doors for locking and unlocking the same, an endwise movable means disposed transverse to said bolts and connected with said bolts and hooks for operating the same, and a locking hasp on the outside of said wall for one of the doors and connected with said means for actuating the same.

7. The combination with a wardrobe trunk having a rigid body adapted to stand on one end and divided vertically into outwardly opening wardrobe and chiffonnier sections with two doors hinged to the body, one for each section and closable toward an upright wall of the body between said doors, of a locking mechanism for said doors, comprising lugs carried by the respective doors at their free edges with lugs on one door entering slots in said wall when said door is closed against the same, a locking hasp on the outside of said wall for the other door, movable locking members on the inside of said wall for both sets of said lugs, and means connecting the hasp with the movable locking members whereby the latter may be simultaneously moved by the hasp into and out of locking engagement with the lugs on both doors.

8. The combination with a wardrobe trunk having a rigid body adapted to stand on one end and divided vertically into wardrobe and chiffonnier sections with two doors hinged to the body, one for each section and closable against an upright wall of the body between said doors, of a locking mechanism for said doors, comprising locking members carried by said wall for the respective doors and cooperating therewith for locking and unlocking the same, a locking hasp on the outside of said wall for one of the doors, and means connecting the movable locking members for both doors with said hasp for simultaneous

operation thereby, said hasp being rotatably mounted on said wall and movable between horizontal and vertical positions in the locking and unlocking of said doors.

9. The combination with a wardrobe trunk having a rigid body divided into wardrobe and chiffonnier sections with two doors hinged to the body, one for each section and closable against an upright wall of the body between said doors, of a locking mechanism for simultaneously locking and unlocking said doors, said mechanism including bolts and hooks and an endwise movable means on the inside of said wall, said bolts being operated in a straight line from said means by a rack and pinion connection therewith, and a locking hasp on the outside of said wall for one of the doors and connected with said means for actuating the same.

In testimony whereof I affix my signature this 25th day of March, 1926.

FRANK W. MEYER.
